CLAIM

The ornamental design for a face mask, as shown and described.

DESCRIPTION

FIG. 1 is a front view of a face mask showing my new design.

FIG. 2 is a rear view of the face mask.

FIG. 3 is a left side view of the face mask.

FIG. 4 is a right side view of the face mask.

FIG. 5 is a top view of the face mask.

FIG. 6 is a bottom view of the face mask; and,

FIG. 7 is a perspective view of the face mask in an opening state.

The broken lines shown in middle part of the face mask illustrate portions of the face mask that form no part of the claimed design, and the broken lines along the edge illustrate stitching lines that form part of the claimed design.
